TICKET PRINTING OR MARKING AND
ISSUING MACHINE

William Percy Harris, Romford, England

Application January 13, 1933, Serial No. 651,607
In Great Britain February 29, 1932

33 Claims. (Cl. 235—31)

This invention relates to machines for printing and issuing tickets and has more particular application to the issue of tickets on omnibuses and tramways although its application is not limited in this respect. The invention has particular reference to ticket issuing machines of that kind in which a ticket whose value or other essential principle is variable, is printed upon and severed from a paper web which is gradually fed from a supply roll as printing and issuing proceeds.

The object of the present invention is to provide an improved machine of the character and for the purposes above stated which will be more convenient and certain in operation, whilst possessing wider capabilities of usefulness than those hitherto in use.

According to the invention a machine is provided for issuing tickets of the kind in which a ticket of variable value is printed upon and severed from a paper web, wherein a reciprocal pressure element co-operates with an inked ribbon, and wherein a plurality of adjustable rotary printing elements are mounted in a fixed plate for the purpose of printing and issuing tickets.

The invention also consists in a machine for issuing tickets of the kind in which a ticket of variable value is printed upon and severed from a paper web wherein a plurality of fare or value keys are provided operatively connected with an adjustable fare value printing element, means being provided to enable the total value to be printed on the ticket when more than one key is operated.

The invention further consists in a machine for issuing tickets having a stationary printing element with adjustable dies therein for printing value, class, stage, date or like markings and a reciprocating carriage co-operating with said plate which prints a ticket during travel in one direction and ejects and severs the printed ticket during its return movement.

According to another feature of the invention a machine for issuing tickets is provided having a printing element with adjustable dies therein for printing value, class, stage, date or like markings wherein the stage printing die is capable of reversal and means are provided to identify the stage marking printed for an outward or inward journey.

The invention still further consists in a machine for printing tickets with variable markings thereon on a paper strip and for severing the printed tickets comprising a plurality of rotary printing devices and an operating mechanism adapted to

be reciprocated in a direction parallel to the axis of rotation of said printing devices to effect printing and issue of a ticket.

Reference will now be made to the accompanying drawings which illustrate by way of example a machine constructed according to the invention for issuing tickets on public vehicles and in which:—

Fig. 1 is a longitudinal sectional elevation of the machine showing the main spindle and parts mounted thereon.

Fig. 2 is a front elevation with the cover of the indicating mechanisms removed.

Fig. 3 is a plan of the machine.

Fig. 4 is a cross sectional view showing the means for locking the fare value setting mechanism.

Fig. 5 is a cross sectional view showing the class selecting mechanism.

Fig. 6 is a detail view of the fare value keys. 20

Fig. 7 is an end view of the devices shown in Fig. 6.

Fig. 8 is a side elevation and Figs. 9 and 10 are reverse end elevations of the feed disc.

Fig. 11 is a detail view of the devices for setting 25 the class and stage printing elements.

Fig. 12 is an end elevation of the devices shown in Fig. 11.

Fig. 13 is a plan of the base plate and carriage.

Fig. 14 is an elevation of the parts shown in 30 Fig. 13.

Fig. 15 is a bottom plan of the carriage.

Fig. 16 is an elevation of the ribbon feed and numbering mechanism.

Fig. 17 is a detail elevation showing the means 35 for locking the printing wheels.

Fig. 18 is a plan of the locking mechanism shown in Fig. 17.

Fig. 19 is an end elevation of one of the inner walls of the casing showing the guillotine mechanism. 40

Fig. 20 is a plan view of a ticket.

Fig. 21 is an elevation of the repeat key mechanism detached.

Fig. 22 is a side elevation of the means to actuate the sleeve associated with the cash counter mechanism of the repeat key mechanism. 45

Fig. 23 is a detail of the means to lock the printing wheel against zeroizing movement, and

Fig. 24 is an end elevation of the parts of the 50 repeat key mechanism operative when issuing tickets for which no cash is taken.

The machine comprises a casing upon the exterior of which are windows through which can be observed counting devices 2, 3, 4 and 5 55

which indicate respectively the total amount of cash received, the total value of exchange or no-value tickets issued, the total number of tickets issued and the total number of exchange or no-value tickets issued. Through the front of the machine also projects an operating handle 6 and beneath the base of the machine is a magazine 7 in which a roll of paper 8 is disposed from which the tickets are formed as hereinafter described.

Through the top of the casing project four fare or value keys 9, 10, 11 and 12 the individual values of which can be varied in accordance with the class of work for which the machine is to be employed. Adjacent these fare or value keys is an adjustable key 13 controlling the class of ticket to be issued and this key works in a slot 14 adjacent which is a notched sector 15 the notches in which correspond in number with the number of different classes of tickets which the machine is capable of issuing such as return, workmen's, children's and the like and which are indicated by abbreviations on a scale 16 adjacent the slot 14.

Also projecting through the top of the machine is the operating lever 17 of a stage indicator the position of which can be adjusted at the end of an outward journey so that the indications which appear through a window 18 in the top of the casing of the fare stage through which the vehicle is travelling operate in the reverse direction on the inward journey.

Within the casing is disposed a horizontal spindle 19 upon which are mounted either directly or indirectly the various adjustable printing elements comprising a fare or value printing wheel 20, class printing wheel 21, stage printing wheel 22, and date printing wheels 23. All of these wheels project into slots in a printing plate 24 mounted horizontally below the spindle 19. Immediately beneath the said printing plate extends a ribbon 25 which is progressed from a reel 26 at the one end to a reel 27 at the opposite end by step-by-step movements as the machine is operated in the manner of a typewriter ribbon.

Beneath the ribbon 25 the paper ticket strip 8 is caused to pass and printing is effected by means of a roller 28 mounted on a carriage 29 which is caused, by operation of the handle 6, to travel from one end to the other of the printing plate 24. On the reverse movement to take the roller 28 back to its original position the roller is moved downwards from its operative position and a pair of gripping devices 30 is thereby brought into operative position to grip the paper strip 8 and feed it forwards so that the printed portion projects through a slot 31 in one end wall 32 of the casing 1.

Having thus described in general terms the functions of the machine the details of the mechanism will now be dealt with.

Fare value setting mechanism. (See Figs. 1, 4, 6, 7, 8, 9, 10, 13-15 and 17.)

The four fare or value keys 9, 10, 11 and 12 are formed at their lower or inner ends with fingers 33, 34, 35 and 36 having slots 37 therein which are engaged by guide members 38 projecting from a fixed portion 39 of the casing 1. Extending between these fingers and the top of the casing are springs 40 which return the keys to normal position after operation. The fingers on the lower ends of the keys are adapted to engage pins 41 extending parallel to the spindle 19 and mounted in a feed disc 42 loosely mounted

on said spindle and partially rotated by the movement of the operating keys, this movement being communicated to the fare or value printing wheel 20 which is thus moved by depression of the keys through a distance proportional to the value indicated on the key depressed to bring the appropriate value die into printing position. In order definitely to position the feed disc the pins 41 are arranged so that at the limit of the stroke of a finger 33, 34, 35 or 36 one of the pins 41 comes into contact with the side of the finger and thus prevents further rotation of the feed disc until the particular finger which has operated the disc is released. The feed disc carries fast thereon an arm 43 which normally engages a fixed stop 44 on the casing, this stop marking the zero position to which the feed disc is returned after the printing wheel 20 has been operatively positioned. The spindle 19 has connected thereto one end of a spring 45 which passes over a pulley 121 and whose opposite end is anchored at 46 to the end wall of the casing so that as the spindle is rotated to advance the fare or value printing wheel 20 the spring 45 becomes coiled around the spindle 19 and placed under tension until the locking means are withdrawn when the spring automatically restores the spindle 19 and parts carried thereby to the zero position.

Mounted on the feed disc is an arm 47 carrying a feed pawl 48 and fixed on the spindle 19 are two ratchet wheels 49 and 50 with a cam 51 between them. In the normal or rest position the feed pawl engages the ratchet wheel 49 whilst a non-return pawl 52 rests upon the ratchet wheel 50. The non-return pawl 52 is mounted upon a tubular spindle 53 from which depends a lever 54 whose lower end engages a slot 55 in a bell crank lever 56 pivoted to the base plate 57, the opposite end of said lever carrying a stud 58 adapted to be engaged by a hook 59 on the end of a carriage release lever 60 also pivoted to the base plate, the engagement between the two levers 56 and 60 being effected to cause the pawls 48 and 52 to disengage from the ratchet wheel 50 during the issue stroke by a lever 61 on the carriage 29 engaging the stud 58.

Also mounted on the tubular spindle 53 is a pawl release lever 62 adapted to be engaged by an error key 63 provided so that if an incorrect value set up on the fare or value printing wheel is discovered before the carriage 29 is moved, pressure applied to the error key 63 by means of a handle 122 on the top of the casing will rock the pawl release lever 62 and the tubular spindle 53 to lift the non-return pawl 52 and feed pawl 48 and allow the spring 45 to zeroize the spindle 19. In the event of zeroizing taking place in these circumstances no record is made as the recording mechanism is not set in motion until the return or issuing stroke of the carriage.

Within the tubular spindle is disposed an inner spindle 64 which carries a carriage lock operating lever 65 consisting of two arms one of which normally rests upon the cam 51 and the other 65a rests normally clear of the disc 42 in the position shown in Fig. 4. The spindle 64 also carries a carriage lock lever 66 the lower end of which normally passes through a slot 67 in one of the carriage guides 68 and enters a slot 69 in the base plate of the carriage. In the rest position the lever 66 is held in the locking position because its operating lever rests upon the cam 51.

When a value is set up, however, the cam 51

is moved from engagement with the crank or lever 65 but the double lever cannot move sufficiently to unlock the carriage because a longitudinal, peripheral groove 70 in the feed disc has 5 been carried out of the path of the end of the lever 65a. When the feed disc 42 returns to normal position, which it does as soon as pressure is removed from the fare or value key, the cam 51 does not return as the ratchet wheels 49 and 50 are held in the adjusted position by the non-return pawl 52. The double lever 65, 65a can then fall, the lever 65a entering the groove 70 thus rocking the spindle 64 and carriage lock lever 66 to release the carriage for movement.

15 Connected to the periphery of the feed disc 42 is a spring 71 anchored to a fixed portion of the casing at 123 and becoming partially wound on the feed disc as the latter is operated. The spring is thus tensioned and restores the disc to 20 normal position when the operating key 9, 10, 11 or 12 is released. When two or more of these 25 keys are operated in succession the feed disc is moved a proportionate amount to bring the fare or value printing wheel to a position in which the amount printed will be the sum of the values indicated on the keys depressed.

Class selecting mechanism. (See Figs. 1, 5, 11 and 12.)

30 The key 13 has pivoted to it a pawl 72 which engages the teeth of the notched sector 15, the pawl 72 having formed integral therewith a thumb piece 73 between which and the handle 74 of the key 13 a spring 75 is disposed to hold 35 the pawl in the desired position of adjustment. Also attached to the key 13 is an indicating finger 76 which moves over the scale 16 and indicates the class of ticket being issued.

35 The lower end of the key 13 is formed as a toothed sector 77 surrounding and engaging a pinion 78 fast on a sleeve 79 rotatably mounted around the spindle 19, this sleeve carrying near its opposite end the class printing wheel 21 which can thus be adjusted in position independently 40 of the fare or value wheel 20.

Stage printing mechanism. (See Figs. 1, 11 and 12.)

45 The stage printing wheel 22 is carried by a sleeve 80 freely mounted around the sleeve 79 and is driven through a ratchet wheel 81 with which either of a pair of pawls 82 and 83 is 50 adapted to engage. These two pawls which are connected by a spring 84 are mounted in a bracket 85 connected to the stage setting lever 17. The bracket 85 is slidably mounted in a fixed frame 86 between which and the sector 77 is a pivotal connection 87 to allow movement to the sector and the frame is provided with two notches 88 and 89 into which studs 90 and 91 on the two 55 pawls 82 and 83 are adapted to engage one at a time.

60 Fixed to the mid-portion of the frame 86 is a leaf spring 92 the outer ends of which bear beneath the studs 93 on the ends of the bracket 85 and oppose the depression of the lever 17. The ratchet wheel 81 and the stage printing wheel 22 are moved by the action of either of the pawls 82 or 83 according to which notch 88 or 89 is engaged 65 by one of the studs 90 or 91. At the end of an outward journey a slight horizontal movement is imparted to the lever 17 so as to change the pivotal point constituted by one of the studs 90 or 91 around which the lever 17 and bracket 85 70 make a slight pivotal movement when normally

depressed to actuate one of the pawls and move the ratchet wheel 81 and printing wheel 22 another stage. The changing of the pivotal point brings one of the pawls 82 or 83 out of and another into, operative position so that the printing wheel 22 and the visible indicator 94 will move in reverse direction on an inward journey. Fast with the stage printing wheel 22 is a gear wheel 95 meshing with a pinion 96 which in turn drives a gear wheel 97 operating the indicator 94 visible 10 through the window 18.

15 Also operated by the reciprocatory movement of the bracket 85 is a printing member 98 which is caused to project through a slot 99 in the printing plate 24 during either the outward or return 20 journey to print a mark on the ticket to indicate the direction of the journey on which the ticket is issued. Thus, for example, a stage number on the ticket in addition to a mark printed by the member 98 would indicate that the ticket was issued on the outward journey whilst the same stage number without the mark printed by the member 98 would indicate that the ticket was issued on the inward journey.

25 The member 98 is formed with a slot 98a at 30 its upper end this slot being engaged by a pin 98b on the bracket 85 whereby when the latter is moved to change its pivotal point the member 98 is rocked about the axis of spindle 19. This rocking movement in one direction brings the member 98 into operative position and in the other direction moves it out of operative position.

Dating mechanism. (See Figs. 1 and 17.)

35 Surrounding the sleeve 80 is a sleeve 100 carrying 40 the dating wheels 23 which are adjusted by hand at the beginning of each day and to simplify the dating of tickets the months are omitted and a number printed on the ticket according to the day of the year on which the ticket is issued. The 45 dating wheels are prevented from moving from their correct positions by light leaf spring 101 (Fig. 17) which engage notches in the peripheries of these wheels.

50 The spindle 19 and the various elements carried thereby are supported in bearings 102 (Fig. 1) carried in fixed portions of the framework and engaging around the dating wheel sleeve 100, the stage wheel sleeve 80, the class wheel sleeve 79 and a boss 104 on the spindle 19 adjacent the fare 55 or value wheel 20.

Serial number printing mechanism. (See Figs. 1 and 16.)

55 Mounted coaxially with the spindle 105 of the driven ribbon spool 27 is a lever 106 whose lower end has an offset arm 107 engaged by a stud 103 projecting laterally from the carriage 29 at the end of its return stroke to rock the lever 106 from its normal position. The lever 106 has a pin and 60 slot connection 108 with an arm 109 adapted to operate a series of number wheels 111 which project through a slot 110 in the printing plate 24 and print a serial number on each ticket, this 65 number being changed by the rocking movement imparted to the lever 106 as above described. The 70 number printing wheels are disposed within a housing 120.

Ribbon feed mechanism. (See Figs. 1 and 16.)

75 The lever 106 carries a pawl 112 having a bent portion 113 at one end urged into engagement with a ratchet wheel 116 by a spring 114 and as the lever is rocked at the end of each issue stroke of the carriage 29 by the stud 103 projecting from 75

the side of the carriage the pawl 112 engages the said ratchet wheel 116 on the spindle of the spool 21 and imparts a partial rotary movement to said spool to progress the ribbon 25 through the machine. When the ribbon has become fully wound on the spool 27 the operator by using a handle specially provided to engage the spindle 117 (Fig. 2) of spool 26 which spindle extends to the exterior of the casing, can re-wind the ribbon on to spool 26 from which it is again withdrawn by the intermittent movements of the pawl 112. When the pawl 112 is out of engagement with the ratchet wheel 116 movement of the latter is prevented by a pawl 118 mounted on the casing and caused to remain in engagement with the ratchet wheel by a spring 119. This pawl 118 is so arranged, however, that the ratchet wheel can slip past it when impelled by the pawl 112. The spool 27 is frictionally mounted on its spindle 105 so that in the event of the operator neglecting to re-wind the ribbon on spool 26 the continued operation of the ratchet wheel 116 will cause the spindle 105 to slip relatively to the spool 27 and thus avoid breakage of the ribbon.

25 *Registering mechanisms. (Figs. 2, 4 and 5.)*

The spindle 19 carries a spur wheel 115 (Fig. 1) meshing with an intermediate spur wheel 124 which in turn drives a third spur wheel 125 loosely mounted on a spindle 126 on the exterior of the main casing and which carries a spur wheel 127 through which either of the cash counters 2 or 3 is adapted to be driven. The spur wheel 125 is coupled to the spindle 126 at the end of each printing stroke by means of a finger 128 (Fig. 14) which projects upwards from the carriage 29 and moves a sliding member 129 engaging a clutch member 146 which is rotatable with the spindle 126. This clutch member 146 has projecting pins 130 which engage in the periphery of a notched disc 131 fast with the spur wheel 125 whereby the latter becomes locked to the spindle 126 and is temporarily held in this position by a catch 132 freed for movement by the clutching operation and moved by a spring 133 into engagement with the rear face of the sliding member 129.

The intermediate spur wheel 124 carries an abutment 134 adapted to engage a rocking lever 135 which is so positioned as to stop rotation of the spur wheel 124 and spindle 19 at the position corresponding to the maximum value of ticket which the machine is designed to issue.

When the fare spindle 19 and parts carried thereby return to zero position the abutment 134 is stopped by the end of a rocking lever 217.

The cash counters 2 and 3 are carried by a plate 136 slidable in roller guides 137 and 138 on the exterior of the main casing 1, a spring 139 tending normally to urge the plate 136 upwards whereby the total exchange counter 3 is driven through a pinion 147 meshing with the spur wheel 127. When the class selecting key 13 is moving over that portion of the scale 16 on which are indicated the exchange and other tickets for which no cash is taken the key 13 occupies the position shown in Fig. 5 wherein a finger 141 of less radius than the remainder of the sector 77 is in contact with a pin 142 on an arm 143 fixed on a shaft 144 from which project arms 145 engaging the plate 136. In this position the shaft 144 is enabled to make a slight clockwise movement (Fig. 5) whereby the arms 145 aided by the spring 139 lift the plate 136 so that the pinion 140 is brought out of engagement with the spur wheel 127 and a pinion 141 brought into

engagement with said wheel. When the key 13 is moved to bring the portion 148 of the edge of the sector 77 into contact with the pin 142 the shaft 144 is given a counter-clockwise movement to lower the plate 136 so that the total cash value counter is again operated. Beneath the spur wheel 125 is mounted a pivoted lever 149 having a pin 150 thereon which pin is engaged by a pin 215 on the wheel 125 to rock the lever 149 to remove the catch 132 from the path of the clutch operating member 129 so that the latter can return to normal position and the drive to the counters is disconnected.

The upward movement of the slidable plate 136 is limited by a stop 151. The spindle 152 of the serial number printing wheels 111 is extended to the exterior of the machine where it passes through a fixed collar 153 on which is mounted a pawl 154 engaging a ratchet wheel 155 on the spindle 152. This spindle also carries a loose sleeve on which is mounted a bevel wheel 156 meshing with a bevel wheel 157 on the spindle of the counter 4 which indicates the total number of tickets issued by the machine. To arrive at the total number of tickets for which cash has been taken the total indicated by the counter 5 is subtracted from the total indicated by the counter 4.

The counter 5 which indicates the total number of tickets issued for which no cash is taken is also mounted on the slidable plate 136 so that an arm 158 through which the counter 5 is driven from the return movement of the carriage is rendered inoperative when the plate 136 is lowered to bring the total cash counter 2 into operation. The arm 158 is engaged on the return movement of the carriage by a pawl 159 movable against a spring 160.

The above described registering mechanisms are enclosed by a casing member 161 having observation windows 162 therein.

Printing wheel locking mechanism. (Figs. 17 and 18.)

During the printing stroke of the carriage 29 the fare or value printing wheel 20, the class printing wheel 21 and the stage printing wheel 22 are locked in position by means of a sliding plate 163 having laterally extending arms 164 terminating in fingers 165 which engage in perforations 166 formed as a circular series in each wheel. The plate 163 has a slot 167 in one edge engaged by a bell crank lever 168 urged by a spring 169 bearing on the lever and on a framework member 170 and normally operates to hold the lever 168 and plate 163 in the locking position. When, however, the carriage 29 is in its rest position it engages and holds the lever 168 which is rocked slightly to maintain the plate 163 inoperative so that the printing wheels can be set. Throughout the operation of the carriage, however, these wheels are locked against movement as the lever 168 is free.

Operating mechanism. (Figs. 1, 13, 14 and 15.)

The operating handle 6 is pivotally mounted on the carriage 29 which is adapted to be reciprocated between the guides 68 mounted on the base plate 57 of the machine. The carriage has mounted on its underside two pawls 171 which co-operate with ratchet teeth 172 in the guides in such manner that once the carriage has commenced to move it is necessary to make the full outward and inward movements before it can return to zero position. The carriage 29 carries the pressure roller 28 by which printing is effected and

the two gripping members 30 which progress the paper strip 8 to the exit 31 after the printing operation has been completed. Between the two guides 68 is a rib or fence 173 which is adapted to 5 be engaged by a stud 174 formed on an arm 175 movable with the handle 6, said stud projecting downwardly through a slot 176 in the base of the carriage and moving along one side of the rib 173 on its outward movement and on the other side of 10 its return movement. The change of position of the stud 174 is effected by reversal of the position of the handle 6 for the return stroke and also causes a collar 177 on the stud to bear on a cam 178 forming part of a bracket 179 which carry the 15 roller 28 so as to depress the latter and the gripping members 30 during the return movement.

The brackets 179 which carry the roller 28 and the gripping members 30 are carried by a pin 180 pivotally mounted in side frames 181 extending 20 upwardly from the base of the carriage 29, to which the handle 6 is pivoted and the roller 28 and gripping members are normally urged upwardly by springs 182 bearing beneath the roller pivots 183 and having an abutment in grooves in 25 a transverse pin 184 carried in the side frames 181.

The stud 174 passes through the forked end 185 of the pawl trip lever 61 pivoted on the base plate 29 and projecting laterally from the carriage. Projecting laterally at the opposite side of the carriage is a roller 186 which operates the guillotine as hereinafter described.

When the position of the handle 6 is reversed for its return stroke the stud 174 moves from one side of the slot 176 to the other and in doing so renders inoperative one of the pawls 171 and allows the other to become operative under the influence of its spring 187. The pawl 171 which is operative, however, will only engage the adjacent rack 172 if alteration in the direction of movement of the carriage is attempted before its stroke is completed.

Ticket severing mechanism. (Figs. 1, 2, 4 and 19.)

45 Adjacent the slot 31 is disposed a plate 188 having therein a slot 189 the lower edge of which forms the fixed blade of a severing device. This co-operates with a movable blade or guillotine 190 slidably mounted between guide rollers 191 disposed between the plate 188 and the end wall 32 of the casing. The blade 190 is moved downwards, when freed by springs 192 engaging over projections 193 on the upper end of the blade and also over fixed abutments 194 on the casing. Pivotally connected to the upper end of the blade 190 is a bent lever 195 whose lower end is raised during the printing stroke by engagement therewith of one end of a lever 196 rocked by pressure thereon of roller 186 on the carriage 29. The left hand end of lever 196 (Fig. 1) is depressed by the roller 186 against the action of a spring 197 which restores the lever to normal position after the return stroke of the carriage. As the bent lever 195 reaches the uppermost point of its travel one end of a pivoted catch 198 engages beneath its lower end due to the action of a spring 199 pressing on the opposite end of said catch. The blade 190 is thus held in raised position until the carriage reaches the end of its return stroke when 50 the end of the carriage presses upon the catch 198 and moves it against the action of its spring 199 so that the lever 195 is no longer supported. The springs 192 are then free to depress the blade 190 sharply and partially sever the ticket from the strip. The blade 190 being of less width than

the paper strip 8, the ticket is not completely severed but can easily be detached by a slight pull. In this manner any danger of a ticket accidentally falling and becoming lost is avoided.

The movement of the lever 195 and consequently of the blade 190 is restricted by a slot 200 engaged by a stud 201 screwed into the casing wall 32.

The roll of paper ticket strip 8 is mounted loosely on a spindle 202 within the magazine 7 10 and its free end is threaded through a channel 203 and over parallel guide members 204 above which the gripping members 30 extend.

The magazine 7 has a hinged cover 205 to enable the magazine to be recharged at any time, 15 such cover being secured in closed position by means of a pivoted bolt 206 and milled nut 207 which is adapted to be screwed down on the bolt into frictional engagement with a forked projection 208 on the main casing. 20

The back of the machine is provided with a stud 209 adapted to enter a bayonet slot in a plate carried by the user of the machine, the stud 209 being so shaped that the machine can be turned through an angle of approximately 25 135° for the purpose of recharging the magazine.

A completed ticket suitable for use on public vehicles is shown in Fig. 20 wherein 210 indicates the value, 211 the class, 212 the stage, 213 the date and 214 the serial number, the other matter 30 being printed by the stationary portions of the plate 24.

To issue a ticket the sequence of operations in the machine above described is as follows:—

The class key 13 and the stage key 17 having 35 been adjusted to the required positions one or more of the fare or value keys 9, 10, 11 and 12 is or are depressed imparting a proportional degree of rotation to the feed disc 42, ratchet wheels 49 and 50 and the fare or value printing wheel 40 20. During this movement the carriage 29 is locked by engagement therewith of the carriage lock lever 66. As soon as the fare or value keys are released by the operator their springs 40 restore them to normal position leaving the 45 spring 71 free to restore the feed disc to normal position. The ratchet wheels 49 and 50, however, are held in the adjusted position by the non-return pawl 52 and as soon as the disc 42 is zeroed the lever 65a falls into the groove 70 50 in the feed disc, thereby rocking the lever 66 to its inoperative position and releasing the carriage 29 for operation.

The carriage is next moved by operating the handle 6, all printing wheels being locked during this stroke by means of the sliding plate 163. The roller 28 pressing the ribbon and the ticket strip against the plate 24 during this stroke causes a ticket to be printed. If this ticket is one for which no cash is received the counter 5 66 is operated during this stroke, the ratchet wheels 49 and 50 remaining locked as lever 66 cannot return to its normal position until the carriage returns. As the printing stroke progresses the guillotine is raised by the rocking movement imparted to the lever 195 and at the conclusion of the printing stroke the clutch 166 is thrown into operation to enable the cash counter to be operated.

On the return or ticket issue stroke the roller 70 28 is lowered and the gripping members 30 are rendered operative so that during this stroke the ticket strip is moved forwardly by the length of one ticket until at the end of the stroke the completed ticket projects through the slot 31. 75

Due to operation of the bell crank lever 56 both pawls are lifted from the ratchet wheels 49 and 50. At the end of the stroke the printing wheels are unlocked and the fare printing wheel is zero-5 ized by the action of the spring 45. As the spindle 19 rotates during this zeroizing movement the appropriate cash counter is actuated and as the carriage lock lever 66 slips into locking position the guillotine is operated for the severing 10 of the ticket from the strip. At the completion of a cycle of operations the lever 66 in returning to locking position engages the end of lever 60 to rock this lever which disengages the hook 59 from the stud 58 and allows the bell crank lever 15 56 to be rocked by a spring 216 to rock the lever 54 and restore the pawls 48 and 52 to engagement with their respective ratchet wheels 49 and 50 and the machine is ready for a further cycle of operations.

20 It is to be noted that no operation of the carriage 29 is possible until a value has been set up on the fare value printing wheel 20 to move the locking lever 66 to inoperative position.

When the machine above described is to be 25 used on vehicles making relatively short journeys where the maximum does not exceed one shilling, the four fare value keys can conveniently be arranged so that they represent the values $\frac{1}{2}d$, 1d, 2d, and 3d, these values being marked on 30 the heads of the keys as shown in Fig. 3. When a required value is not represented by the values marked on the keys, it is only necessary to depress two or more keys to make up the required value, and the sum of the values of the keys depressed will be printed on the ticket issued. Thus 35 if the 1d key be depressed twice a 2d ticket will be issued and if the 2d and 3d keys be depressed in succession a 5d ticket will be issued. The fare or value printing wheel 20 may have dies on its 40 surface for all values increasing by $\frac{1}{2}d$ stages from $\frac{1}{2}d$ to 1/- this last value being obtained by depressing the 3d key four times. It is to be understood, however, that the machine is not limited to this range of values which can readily 45 be extended, by suitably altering the fare value setting mechanism, to issue tickets up to £1 or higher values according to requirements.

The machine may also, if desired, be fitted with a repeat key so that when duplicate tickets are 50 to be issued, operation of the keys 9-12 may be rendered temporarily unnecessary.

The said repeat key mechanism may take the form illustrated in Figs. 21-24 wherein the spindle 19 carrying the fare or value printing wheel 20 carries a gear wheel 115 as before for driving the cash counting mechanism. In the present instance, the gear wheel 115 actuates a train of gears 229 which drive a pinion 221 fast on a rotatable spindle 222 on which a sleeve 223 is 55 slidably but not rotatably mounted. The sleeve 223 is formed at one end with a series of annular rack teeth 224 and also with a number of radially projecting pins 225 arranged in a helical series as shown in Fig. 21. The movement of the sleeve 60 is limited in one direction by a pin 226 on the spindle 222 engaging a notch or slot 226^a in the sleeve, whilst movement of the sleeve in the opposite direction compresses a spring 227 abutting against a fixed portion 228 of the framework, 65 said spring serving to return the sleeve to the normal position shown in Fig. 21, after operation. The rack teeth 224 engage a pinion 229 on a spindle 230 by which a cash counter 231 is driven through bevel gears 232.

70 From the foregoing, it will be clear that under

normal conditions of operation, setting of the fare or value wheel 20 will also impart a partial rotation to the sleeve 223 so that when the carriage is moved through its outward or printing stroke, a projection 233, on a lever 242, pivotally mounted at 233^a on the side of the carriage 29 (Fig. 22), will engage the pin 225 which lies in its path and move the sleeve 223^a along its spindle, thereby imparting a movement to the pinion 229 and counter 231. A return spring 242^a 10 is connected to carriage 29 and to lever 242. The higher the value of the ticket issued, the earlier will a pin 25 be engaged by the projection 233 so that greater movement will be imparted to the sleeve and counter. 15

When a number of tickets of the same value are issued, the operator moves a key 234 (Fig. 23), slidably mounted on the top of the machine and which carries a projection 235 adapted to engage one of the holes 166 in the printing wheel 20 so as to lock the wheel against return movement to zero position irrespective of the operation of the locking plate 163. This locking operation will also lock the spindle 222 and sleeve 223 against rotation so that as long as the printing wheel 20 remains locked, continued reciprocation of the carriage will cause the repeated issue of tickets all of one value and the sleeve 223 will be reciprocated through the same distance at each operation; operation of the keys 9-12 being unnecessary. 25

When issuing tickets for which no cash is taken, a pin on the sector 71 of the class selecting mechanism engages a lever 236 (Fig. 24), having a fixed pivot 237 and having a pin 238 30 engaging a notch or slot 238^a in a lever 239, pivoted at 239^a and having a plate 240 at its lower end which presses on a stud 241 carried by the aforesaid lever 242, to move the projection 233 to a position in which it will pass between the pins 225, instead of engaging them. Thus when no cash is taken, the counter is not actuated as the ticket is printed and issued. 35

It is to be understood that although the machine has been described herein with particular 40 reference to its application for issuing tickets on public vehicles the scope of the invention is not limited in this respect as machines constructed according to the invention can also be used for many and various purposes, e. g., the issue of 45 tickets in shops, in theatres, railways and in packing departments of manufacturing firms where it is desirable to insert in each package an identification slip bearing various particulars as to the origin of the goods. Such applications as 50 these would require no substantial alteration in the mechanism above described but only in the form of the ticket and the matter printed by the various mobile printing members. 60

I claim:

1. A machine for issuing tickets comprising a casing, a stationary printing element therein, adjustable printing elements in the casing for printing value, class, stage and date in cooperation with said stationary printing element, a carriage reciprocable in a rectilinear path in said casing and cooperating with said printing elements to print on a web through travel of the carriage in one direction and to advance the printed web relatively to the casing during travel of the carriage in the opposite direction to facilitate removal of the ticket, and means for automatically severing the printed ticket portion from the remainder of the web through opera- 70 75 80 85 90 95 98

- tion of the carriage adjacent the end of said advancing movement.
2. A machine for issuing tickets comprising a casing, printing elements therein including adjustable dies for printing value, class, stage and date on a web, means for progressing said web through the casing, means reciprocable in a rectilinear path cooperating with said printing elements to impart printing movement to the web and effect the advance of the printed portion thereof, and means for reversing the stage printing die to identify the stage marking on an outward or return journey.
3. A machine for printing a web to produce tickets comprising a casing, settable printing means therein, a carriage in the casing mounted for reciprocation beneath said printing means, an element on said carriage bearing upon the web during reciprocation of the carriage in one direction to move the web to effect the printing thereon, an inking means for the printing means operable between the web and the printing means, and gripping means on said carriage operating during movement of the carriage in the opposite direction to advance the printed portion of the web for removal.
4. A machine for issuing tickets comprising a casing, means for feeding a web therethrough, a plurality of value keys carried by said casing, a value printing element carried by said casing, means to adjust said printing element through operation of said keys, a reciprocating carriage within said casing having an element to engage and move the web to effect the printing during movement of the carriage in one direction, gripping means on the carriage to advance the printed portion of the web for removal through movement of the carriage in the opposite direction, and means for locking said carriage against movement when no value is set up on the value printing element and during the period when said keys are being operated.
5. A machine for issuing tickets according to claim 4 including means for zeroizing the value printing element at the end of movement of the carriage in the web-feeding direction, and means for ensuring full reciprocating movement of the carriage when moved from its zero position and before the value printing means can be zeroized.
6. A machine for issuing tickets according to claim 4 having means for zeroizing the value printing element at the end of movement of the carriage in the web-feeding direction, and means to prevent retrograde movement of the carriage between zero position and zeroizing position of the value printing means.
7. A machine for issuing tickets according to claim 4 including track members on which said carriage moves, means for depressing said element of the carriage at the conclusion of printing, and means to bring said gripping means into operation to grip the web and issue a printed ticket during the return stroke of said carriage.
8. A machine for issuing tickets according to claim 4 including a ticket severing blade, and means on the carriage to operate said blade to sever the ticket on the movement of the carriage to zero position following advance of the printed portion of the web for removal.
9. A machine for issuing tickets comprising a casing, means for progressing a web therethrough, a spindle in the casing, a rotary element freely mounted on said spindle, a set of value keys for operating said rotary element, a value printing wheel on said spindle coacting with said web, means to set said printing wheel through movement of said rotary element, and means for locking said spindle and printing wheel in position for printing.
10. A machine for issuing tickets according to claim 9 including a class printing wheel freely mounted on said spindle, a class selecting key to operate said class printing wheel, value registering mechanism, and means for automatically adjusting said mechanism to bring the appropriate counter thereof into operative position for actuation when tickets, for which no cash is taken, are issued.
11. A machine for issuing tickets as claimed in claim 9 including a reciprocating carriage for effecting the printing and issuing operations, respectively, by movements in opposite directions, value registering mechanisms driven from said spindle, a clutch for coupling said mechanisms one at a time to said spindle, and means for operating said clutch through the movement of said carriage.
12. A machine for issuing tickets according to claim 9 including a stage printing wheel freely mounted relatively to said spindle, a stage setting key for operating said stage printing wheel, means for reversing said key for a return journey, and a printing element cooperating with said key to print an indication of direction of journey on a ticket.
13. A machine for issuing tickets comprising a casing, means for progressing a web therethrough, a plurality of operating keys on said casing, a spindle within said casing, wheels setably mounted on said spindle for printing value, class, stage and date, means operable by said keys to set said wheels, an inked ribbon cooperating with said printing members, reciprocating means for pressing the web and said ribbon into printing relation with said printing elements by movement in one direction and means for advancing the printed portion of the strip to facilitate removal, the last mentioned means being operable through movement of the reciprocating means in the opposite direction.
14. A machine for issuing tickets according to claim 13 including means for printing a serial number upon each ticket issued, means to advance the last mentioned means through a unit of distance upon each reciprocation of the reciprocating means, and a total counter operable by said serial number printing means.
15. A machine for issuing tickets according to claim 13 including means for printing a serial number on each ticket, means including a winding mechanism operable by the last mentioned means for advancing said inked ribbon by step-by-step movements through the machine, and means for enabling wound ribbon to slip under undue strain to prevent breakage.
16. A machine for issuing tickets according to claim 9 including a carriage, guide means therefor, a locking lever on the carriage engageable with the guide means, and means to rock said lever to inoperative position operable by the second mentioned means.
17. A machine for issuing tickets according to claim 3 including a slidable plate, means on said plate to engage value, class and stage printing wheels after setting to lock them against movement, and means to release the last mentioned means through movement of the carriage as it approaches zero position.
18. A machine for issuing tickets comprising

a casing, means for progressing a web therethrough, value printing wheel mechanism including printing elements, reciprocatory means operable to cause said elements to print a ticket and to advance the ticket to facilitate removal, a plurality of depressible value setting keys, a rotatable device operable directly by at least one of said keys, and means whereby the value printing wheel mechanism is moved by said device a distance proportional to the total value of the keys depressed, so that a corresponding total value will be printed on a ticket.

19. A machine for issuing tickets comprising a casing, a magazine forming part thereof for holding a web roll, guides in the base of the casing, a reciprocatory carriage rectilinearly movable on said guides, an operating handle on said carriage extending through the casing, a plurality of printing elements disposed above the carriage, an inked ribbon movable across the surfaces of said printing elements, means on the carriage for actuating the web to cooperate with said ribbon and elements, a plurality of value keys on said casing, and means directly rendering the machine operative for printing the total value when more than one of said keys are actuated.

20. A machine for issuing tickets comprising a casing, means for progressing a web therethrough, a plurality of settable printing elements coacting with the web, a plurality of keys operable to directly set said elements, a rectilinearly movable carriage in the casing, means on said carriage operable as the carriage reciprocates in one direction to cause said elements to print a ticket, means on said carriage and operable as the carriage moves in the reverse direction to advance the web, and severing means for the printed ticket portion of the web operable by the carriage on its return to zero position.

21. A machine for issuing tickets comprising a casing, means for progressing a web therethrough, an adjustable value printing element, a plurality of adjustable printing elements rotatably mounted with respect to said adjustable value printing element, a plurality of value setting keys, means for proportionally adjusting the value printing element to print the total value when more than one key is operated, a reciprocatory carriage for effecting printing and issue of a ticket, and means actuated by movement of said carriage to lock said value printing element when the carriage is out of zero position.

22. A machine for issuing tickets comprising a casing, means for intermittently progressing a web through said casing, means for printing values on said web, a plurality of keys for adjusting said value printing means, reciprocatory means in said casing for moving the web to effect the printing, means on the last mentioned means to advance the web after printing, means for locking said reciprocatory means against movement when no value is set up on the value printing element and whilst the keys are being operated, and means for locking the value printing means during the printing operation.

23. A machine of the class described having a printing plate, printing means to register with the printing surface of the plate in operative position, a carriage manually reciprocable beneath said plate, means on the carriage engageable with a web disposed beneath and normally spaced from the plate during one direction of reciprocation to raise the web for printing thereon, means to retract the last mentioned means after

printing whereby the web will fall to normal position, gripping means on the carriage engageable with the web after said fall to normal position and prior to reciprocation of the carriage in the opposite direction, whereby reciprocation of the carriage in the last mentioned direction will advance the printed portion of the web.

24. A machine for issuing tickets according to claim 22 wherein the reciprocatory means is a manually slid able carriage having printing wheel means and a locking member actuated by said carriage to lock said printing wheels during the operation of said carriage.

25. A machine for issuing tickets comprising a casing having a magazine for a web roll, a spindle in said casing, a plurality of settable printing elements carried by said spindle, a stationary printing plate with which said printing elements cooperate, means for feeding an inked ribbon across said printing elements, means for feeding the web from said roll across the ribbon, a reciprocatory carriage for moving the ribbon and web relatively to the printing elements to effect printing, means on the carriage to advance the web after printing, severing means to engage the web adjacent the end of the printed portion, keys for setting up a value on certain of the printing elements, means for printing the total value when more than one key is operated, means to prevent alteration of said value after movement of the carriage has commenced, and means for registering the operations of the machine and values of tickets issued.

26. A machine for printing tickets according to claim 3 including visible indicating devices, one device being operable through movement of the carriage in one direction to register the tickets issued when no cash is received, and the other device being operable through movement of the carriage in the opposite direction to register the total number of tickets issued.

27. A machine of the class described comprising a casing, means movable in a rectilinear path for progressing a web therethrough, a variable value printing means in the casing coacting with the web, a plurality of independently operable value setting keys urged to retracted position individually, an intermediate operating element urged to normal position having means coacting with said keys to effect different adjustments of the element through successive operation of the keys to correspondingly adjust said printing means for printing on the web the total value of the keys operated, means to urge return of the printing means to normal position after each adjustment, and a device carried by the first mentioned means to press the web against the printing means.

28. A machine of the class described according to claim 27 having means operable to hold the printing means from return to normal position to enable repeat printing.

29. A machine of the class described comprising means for progressing a web, a variable value printing means coacting with the web, a plurality of independently operable value setting keys urged to retracted position individually, an intermediate operating element urged to normal position having means coacting with said keys to effect different adjustments of the element through successive operation of the keys to correspondingly adjust said printing means for printing on the web, means to urge return of the printing means to normal position after each

adjustment, and means operable to cause contact of the web and the printing means.

30. A machine of the class described according to claim 29 having means operable to hold 5 the printing means from return to normal position to enable repeat printing.

31. A machine for issuing tickets according to claim 27 including a plurality of printing wheels for printing fare value, stage, class and date, 10 a horizontal spindle carrying said wheels and extending lengthwise of the machine, and register means operated by said printing wheels.

32. A machine for issuing tickets according to claim 27 having means normally under control

of the rectilinearly movable means for zeroizing the printing element, and means operable to maintain the printing element in set positions irrespective of movement of the rectilinearly movable means, to enable a plurality of tickets 5 of the same value to be printed.

33. A machine for issuing tickets according to claim 13 having means operable to maintain the wheels and spindle in set positions irrespective of movement of the rectilinearly movable means, 10 to enable a plurality of tickets of the same value to be printed.

WILLIAM PERCY HARRIS.
